UNITED STATES PATENT OFFICE

146,257

DESIGN FOR A COMBINED FLASHLIGHT AND KEY CHAIN

Clarence G. Erickson, Chicago, Ill., assignor to
Erickson-Johnson Machine Co., a partnership
composed of Clarence G. Erickson and Elmer L.
Johnson

Application October 25, 1945, Serial No. 123,176

Term of patent 3½ years

(Cl. D48—24)

To all whom it may concern:

Be it known that I, Clarence G. Erickson, a citizen of the United States, residing at Chicago, in the county of Cook and State of Illinois, have invented a new, original, and ornamental Design for Combined Flashlight and Key Chain, of which the following is a specification, reference being had to the accompanying drawing, forming part thereof.

Figure 1 is a perspective view of a combined flashlight and key chain showing my new design.

Fig. 2 is a top view thereof.

Fig. 3 is a bottom view thereof.

Fig. 4 is a side view thereof.

I claim:

The ornamental design for a combined flashlight and key chain, as shown.

CLARENCE G. ERICKSON.
